DESK STAND

William F. Vernon, Newton, Iowa

Application February 7, 1955, Serial No. 34,376

Term of patent 7 years

(Cl. D74—1)

FIG. 1

I claim:

The ornamental design for a desk stand, substantially as shown.
